UNITED STATES PATENT OFFICE.

THOMAS C. CHENEY AND JOHN S. BOSSON, OF CHICKASHA, OKLAHOMA.

ELECTRIC INSECT-DESTROYER.

No. 907,570.

Specification of Letters Patent.

Patented Dec. 22, 1908.

Application filed July 8, 1908. Serial No. 442,530.

To all whom it may concern:

Be it known that we, THOMAS C. CHENEY and JOHN S. BOSSON, citizens of the United States, residing at Chickasha, in the county 5 of Grady and State of Oklahoma, have invented new and useful Improvements in Electric Insect-Destroyers, of which the following is a specification.

This invention relates to electric insect destroyers, and the object of the invention is to provide a rectangular frame having a positive and a negative electric wire upon its sides to establish a normally open circuit, the wires being provided with transverse conductors extending across the frame and connected with an insulated rod, the conductors from each of the wires being spaced a slight distance apart so that a fly or other insect contacting the conductors from the positive 10 and negative wires will close the circuit which is strong enough to electrocute the fly or other insect but which is not strong enough to harm a person coming accidentally in contact with the same.

Another object of the invention is to provide a frame having a normally open electric circuit provided by the positive and negative wires of a conductor, the conductor being provided with a suitable plug adapted to be positioned in any ordinary electric contact 15 socket whereby the device may be easily connected and suspended.

A still further object of the invention is to provide a rectangular frame having a positive and a negative electric wire upon two of its sides, the wires being provided with reversely extending transverse conductors and the frame being provided with a hinged back, said back being provided with a suitable substance 20 adapted to attract flies or other insects to the device.

With these and other objects in view the invention resides in the novel construction and arrangement of parts hereinafter fully 25 described and claimed.

In the accompanying drawing there is illustrated a perspective view of a device constructed in accordance with the present invention showing the same suspended from 30 an ordinary electric conducting socket.

In the accompanying drawing the numeral 1 designates a suitable rectangular frame. Positioned upon the vertically extending arms or members 2 and 3 of the frame 1 is a 35 positive electric wire 4 and a negative elec-

tric wire 5. These wires 4 and 5 are retained upon the arms 2 and 3 through the medium of suitable staples 6, and the wires are brought together approximately central of the upper horizontal end of the frame and 40 twisted together to provide a substantially single conductor 7. The end of this conductor 7 is provided with a suitable contact plug 8 of the ordinary threaded construction, and this plug 8 is adapted to engage with an electric 45 conducting socket 9 also of the ordinary interiorly threaded construction.

Positioned between the upper and lower horizontal members of the frame 1, and adjacent the vertical members 2 and 3 thereof are insulated rods 10. The positive wire 4 is provided with a plurality of spaced conducting wires 11 adapted to be connected with the insulated rod 10 adjacent the vertical member 3 of the frame. The negative wire 5 is also provided with spaced conducting wires 12 which are adapted to be connected with the insulated rod 10 adjacent the vertical member 2 of the frame. The spaced conducting wires 11 and 12 are adapted to extend 50 across the face of the frame one interlacing the other so that a comparatively short space is left between the wires and whereby a fly or other insect contacting the conductors 11 and 12 will close the circuit, 55 the fluid passing through the body of the insect and effectively destroying the same.

The frame 1 is provided with a suitable back 13, hingedly connected with one of the vertical members of the frame as at 14. This 60 back 13 is adapted to be provided with a suitable substance upon its inner face to attract flies or other insects to the device. The back 13 is adapted to be held in closed position against the frame 1 through the medium of 65 a suitable clasp or other securing devices, not shown.

From the above description, taken in connection with the accompanying drawings, it will be noted that we have provided an extremely simple and effective device for exterminating flies or other obnoxious insects, one which may be readily removed from place to place and quickly and easily secured upon any ordinary electric socket.

While the preferred embodiment of the invention is herewith illustrated and described, it is to be understood that minor details of invention within the scope of the following claim may be resorted to without departing 105

from the spirit or sacrificing any of the advantages of the invention.

Having thus fully described the invention what is claimed as new is:

5. In an insect destroyer, a frame, a positive and a negative electric wire upon the frame, said wires being joined and provided with a contact plug, insulated rods upon the frame, conductor members connecting the positive and negative wires to the insulated rods one

adjacent the other, and a hinged back for the frame adapted to receive bait.

In testimony whereof we affix our signatures in presence of two witnesses.

THOMAS C. CHENEY.
JOHN S. BOSSON.
